UNITED STATES PATENT OFFICE.

PHILIP DIEHL, OF ELIZABETH, NEW JERSEY, ASSIGNOR TO THE SINGER MANUFACTURING COMPANY OF NEW JERSEY.

FEEDING MECHANISM FOR BUTTON-HOLE SEWING-MACHINES.

SPECIFICATION forming part of Letters Patent No. 319,801, dated June 9, 1885.

Application filed February 12, 1885. (No model.)

To all whom it may concern:

Be it known that I, PHILIP DIEHL, a citizen of the United States, residing at Elizabeth, in the county of Union and State of New Jersey, have invented certain new and useful Improvements in Feeding Mechanisms for Button-Hole Sewing-Machines, of which the following is a specification, reference being had therein to the accompanying drawings.

My invention relates to a feeding mechanism for button-hole sewing-machines of that kind which is adapted to give the material the proper movements to form straight button-holes, or button-holes which do not have eyelets at one end.

As I propose to apply my invention to sewing-machines having laterally-moving needle-bars and needles to form overedge or over-seaming stitches, the only movements necessary to be imparted to the cloth-clamp in working a button-hole will be a longitudinal movement in one direction to work one side of the button-hole, a lateral movement of the clamp to bar one end of the button-hole and to bring the other side thereof beneath the needle, a reverse longitudinal movement of the clamp to work the other side of the button-hole, and a return lateral movement to bar the other end of the button-hole and to bring the parts to their first position.

My invention comprises certain mechanism for effecting these movements, which may be varied as circumstances may require.

In the drawings, Figure 1 is a side elevation of a "Singer" sewing-machine having mechanism for moving the needle-bar laterally, with my invention applied thereto. Fig. 2 is a detail plan view of the said mechanism for moving the needle-bar laterally. Fig. 3 is a plan view, with the bracket-arm in section, on line *a b*, Fig. 1. Fig. 4 is an end view of the bed-plate and attached parts, as seen from the left of Fig. 3. Fig. 5 is a bottom view of the machine with the shuttle-operating mechanism partly broken away. Fig. 6 is a section on line *x y*, Fig. 5.

A indicates the bracket-arm of the machine, and *a* the horizontal driving-shaft journaled therein, and to the latter is secured a gear-wheel, *a'*, having half the number of teeth

of a larger gear-wheel, *a²*, with which it meshes. The wheel *a²* rotates on a stud or pin supported by the bracket-arm, said wheel being provided on its outer face with a cam-groove, *a³*, entered by a pin or roller on a lever, *a⁴*, pivoted to the bracket-arm. The said lever has on its outer face a slot affording means for adjustably attaching thereto a rod, *a⁵*, connected at its forward end to a vibratory frame, *a⁶*, in which the needle-bar *a⁷* reciprocates vertically. The needle-bar frame *a⁶* is or may be the same in construction as the frame shown by my Patent No. 272,126, dated February 13, 1883. The needle-bar receives its vertical movements from the driving-shaft *a*, and it will thus be readily understood that it will be moved laterally, after each vertical movement, to form zigzag or overseaming stitches.

To the shaft *a* is geared a vertical shaft, *b*, (shown in section in Fig. 5,) this arrangement of shafts being the same as that long in use in the well-known Singer family machines.

On the shaft *b*, beneath the bed-plate *C*, will be a crank (not shown) for operating the shuttle, which may be arranged to oscillate horizontally in a race, *b'*, the shuttle-driver receiving its movements through the arm *b²* and connecting-rod *b³* from the said crank.

As the special needle-bar and shuttle-operating mechanisms above described form no essential part of the present invention, they need not be further referred to.

To the shaft *b* is secured a cam, *d*, working in a yoke on a connecting-bar, *D*, the latter having a pin, *d'*, adjustably secured by a clamp and thumb-screw, *d²*, to the slotted free end of a lever, *E*, pivoted on a stud, *e²*, attached to the bed-plate *C*.

F is the feeding-wheel, which is also pivoted on the stud *e²*, said wheel being provided on its lower face with an annular flange or rib, *f*, and on its upper face with cam-grooves *f'* and *f²*.

To the lever *E* is attached a spring, *e³*, bearing against a cramping feed-dog, *e*, the latter being slotted to engage the rib *f* and having a tail-piece entering a recess in the lever *E*, as shown in Fig. 5. As the lever *E* is vibrated by the connecting-bar *D*, the feed-dog *e* will be caused to bite the rib *f* when moving in one

direction, and thus move the said wheel a step forward, said dog sliding freely over said rib on its return movement, as is common with this class of clutching devices.

- 5 G is the feeding-lever, by which the cloth-clamp H is moved longitudinally the length of the button-holes, said lever being pivoted by a swiveled fulcrum-block, k, carried by an arm, k', of a feed-regulating slide, K, the latter being movable in ways beneath the bed-plate and secured in any desired position by a set screw, k², passing through a slot, c, in the bed-plate, as is common with the feed-regulating devices of the well-known Singer 10 family sewing-machines. The lever G is provided at its rear end with a pin or roller working in the cam-groove f' of the feed-wheel F, the forward end of said lever being loosely connected by a link, g, to a pin, h, on the 15 cloth-clamp H.
- L is a sliding carrying-plate for the cloth-clamp, said plate being movable in ways extending lengthwise of the bed-plate C. The cloth-clamp H slides in ways extending transversely of the said plate L, the latter being connected by a link, l, with a slotted "throw-over" lever, M, pivoted to the bed-plate C, and having at its free end a stud or roller working in the cam-groove f² of the wheel F. The 20 link l is secured in the slot m of the lever M by a clamp and thumb-screw, m', similar to d², and by changing the position of the connection of said link and lever the movements of the slide L may be varied as may be required.
- 25 The material in which a button-hole is to be worked being placed in the cloth-clamp, and the machine, with its laterally-moving needle-bar and needle, being set in motion, the feeding-wheel will be intermittently rotated by the feed-dog, operated, as above described, 30 by the cam d, through the connecting-bar D and lever E. The lever G is vibrated to move the cloth-clamp lengthwise of the button-hole by reason of the above-described 35 connections of the said lever with the cam-groove f' of the feeding-wheel and with the cloth-clamp. By changing the position of the pin d' in the slot of the lever E the movements of the wheel F may be varied to make the 40 movements of the cloth-clamp faster or slower, and thus to change the distance apart of the stitches; and by varying the position of the fulcrum-block k, on which the lever G swings, the throw of said lever may be changed 45 to give such longitudinal movements to the cloth-clamp as will correspond to any desired length of button-hole. When one side of a button-hole has been worked, the throw-over or lateral movement of the cloth-clamp, to 50 bring the other side of the button-hole beneath the needle, will be effected by the slide L, operated from the cam-groove f² of the wheel F through the lever M and link l, as will be readily understood. As this throw-over or lateral movement of the cloth-clamp 55 will not occur suddenly, but will occupy the time required to form several stitches, the but-

ton-hole will be properly finished or barred at each end.

I claim as my invention—

1. The combination, with a sewing-machine having a laterally-moving needle-bar, of a carrying-plate, a cloth-clamp sliding on said carrying-plate, a feeding-wheel having cam-grooves, a feeding-lever loosely connected 75 with said cloth-clamp and operated by said wheel, and a throw-over lever connected with said slide, and also operated by said wheel, substantially as set forth.

2. The combination, with a sewing-machine 80 having a laterally-moving needle-bar, of a carrying-plate sliding in ways extending lengthwise of the bed-plate of the machine, a cloth-clamp movable transversely of the said carrying-plate, a feeding-wheel having cam-grooves, mechanism for operating said wheel, a feeding-lever operated by said wheel and loosely connected with said cloth-clamp, and a throw-over lever operated by said wheel and loosely connected with said carrying-plate, 85 substantially as set forth.

3. The combination, with a sewing-machine having a laterally-moving needle-bar, of a grooved feeding-wheel, its operating mechanism, a carrying-slide, a cloth-clamp mounted 95 thereon, a slotted throw-over lever pivoted to the bed-plate of the machine, and having a stud engaging a groove in said wheel, and a link pivoted to said slide and adjustably connected to the said lever, substantially as set 100 forth.

4. The combination, with the cloth-clamp, its carrying-slide, and the feeding-wheel, of the feeding-lever G, the connecting-link g, the fulcrum-block k, and the adjustable slide K, 105 having an arm, k', substantially as set forth.

5. The combination, with the feeding-wheel, the cloth-clamp, the carrying-slide and intermediate connections between said wheel and the said clamp and slide, of the shaft b, cam 110 d, yoked connecting-bar D, lever E, having one end slotted and its opposite end recessed, spring e², and feed-dog e, having a tail-piece entering the recess in the said lever, substantially as set forth.

6. The combination, with a sewing-machine having a laterally-moving needle-bar, of a cloth-clamp, a carrying-slide for the same, a feeding-wheel, having grooves for operating said clamp and slide, a feeding-lever loosely 120 connected with said clamp and having an adjustable fulcrum, a throw-over lever, a link pivoted to said slide and adjustably attached to said throw-over lever, a feed-dog, a lever for operating the same, a connecting-bar 125 adjustably attached to the latter lever, and mechanism for operating said connecting-bar, substantially as set forth.

In testimony whereof I affix my signature in presence of two witnesses.

PHILIP DIEHL.
